UNITED STATES PATENT OFFICE.

STANLEY CHARLES BRYANT, OF CHICAGO, ILLINOIS.

HIGHWAY-CROSSING SIGNAL

1,379,678.

Specification of Letters Patent. Patented May 31, 1921.

Application filed July 20, 1917. Serial No. 181,712.

To all whom it may concern:

Be it known that I, STANLEY CHARLES BRYANT, a citizen of the United States, and a resident of the city of Chicago, in the 5 county of Cook and State of Illinois, have invented a new and useful Highway-Crossing Signal, of which the following is a specification.

This invention relates to signaling, particularly to railway signaling and more especially to that type of railway signal known as a highway crossing signal.

The invention consists in the constructions and arrangements set forth and described and claimed.

The principal object of the invention is the production of a comparatively simple, inexpensive and reliable signal for location at the crossing of a highway and a railway 20 track for the purpose of warning those on the highway about to cross the railway whether or not a train or car is approaching the highway crossing of the railway.

Other objects and advantages will appear 25 as the description of the invention progresses, and the novel features of the invention will be particularly pointed out in the appended claims.

In describing the invention in detail, reference is had to the accompanying drawing, wherein I have illustrated a preferred physical embodiment of my invention, and wherein like characters of reference designate corresponding parts throughout the 35 several views, and in which—

Figure 1 is a diagrammatic sketch showing my invention; Fig. 2, is a front view of the signal banner of my invention.

As is well known to those skilled in the 40 art to which this invention relates, a closed track circuited trackway is most commonly employed as the means for controlling a highway crossing signal.

In Fig. 1, applicant has shown a section 45 of trackway composed of the two rails 1 and 2. Across one end of this section a battery 3 of any well known and appropriate form has been connected. Across the other end of the section the well known relay 4 has been connected, as by wires 5 and 6. The battery, the rails and the relay together form the well known closed-track-circuited 50 trackway.

When no train or part of a train is upon 55 the rails 1 and 2, the relay 4 is energized and consequently holds its armature 7 in the

upper position as shown. The presence of a train or any part of a train upon the track rails 1 and 2 causes, in the well known manner, the deenergization of relay 4 and the 60 dropping of armature 7 so that it makes contact with wire 8.

Applicant's signal banner proper, 9, a front view of which is shown in Fig. 2 and an end view in Fig. 1, is mounted on a horizontal shaft 10, arranged to be supported and oscillate in the bearing member 11. It is well understood by those skilled in the art to which this invention relates that highway crossing signals are located in close 65 proximity to the crossing for which they are used as a signal and in such position as to be not only readily visible but if possible such that they command attention. Applicant's signal banner has two positions: one, 70 in which the banner is shown in Fig. 1, in which the horizontal shaft supporting the banner is designated 10, in which position the front face of the banner, as shown in Fig. 2, is faced directly downward and the rear face directly upward so that as the banner in section is an elongated diamond shape, as shown by Fig. 1, there is practically only an edge presented to one approaching the banner from either the right or the 75 left as viewed in Fig. 1; the other position of the banner, as shown by Fig. 2, is that in which the banner has been oscillated ninety degrees from the position shown in Fig. 1, that is, so that a word as, Stop, 80 formed on both sides of the banner, is visible to one approaching either from the right or the left as viewed in Fig. 1.

There are then two positions of the arrestive banner 9; one which may be called 85 the non-visible; the other, the visible. To render the visible position not only merely visible but also arrestive, an arrestive word as, Stop, may be formed on the banner sides, or other and well known means may 90 be used for a like purpose.

When the banner is in the visible position it is, in accordance with applicant's invention, an indication that extreme care should be taken in proceeding over the rail- 105 way as a train may be just about to cross the highway.

In order to oscillate the banner applicant has provided a motor 12, which has the usual rotating shaft 13, upon which is fixedly mounted a small gear wheel 14. Gear wheel 14 meshes with gear wheel 15, which is

fixedly mounted on shaft 16, which also has small gear wheel 17 fixedly mounted thereon. Gear wheel 17 meshes with gear wheel 18 mounted to rotate on shaft 19.

5 Gear wheel 18 has a crank pin 20 protruding from the face thereof. A link 21 is connected at one end to crank pin 20, and at the other end to a crank pin 22, protruding from an operating arm 23, which is oscillatably mounted on the shaft 24.

10 Operating arm 23, at its upper end, has fixedly mounted thereon a magnet 25, which may be at times energized by a flow of electricity therethrough. In operative relation 15 with the upper end or one pole of the magnet 25 is positioned an armature 26 fastened in any well known manner, as integrally, with clutch arm 27. This arm 27 together with arm 23 and magnet 25 which is positioned 20 on an extension of 23 form a two-part clutch, the parts of which are held together at times by energizing magnet 25.

15 The clutch arm 27 is formed into a hub at the lower end and is oscillatably mounted 25 on shaft 24. The clutch arm has attached thereto the weight 28 for a purpose to be described, the insulating projection 29 for operation of contact finger 30 and operating link 31 which is connected to operating 30 crank 32 which in turn is fixedly mounted on horizontal shaft 10, best shown in Fig. 2.

With all parts in the positions as shown in Fig. 1, that is with crank pins 20 and 22 in line with the center of shaft 19, any force 35 exerted on link 21 would not tend to rotate gear wheel 18 and even if such a tendency existed no movement of 18 could take place by reason of brake block 51, to be later described. If under such conditions the magnet 40 25 is energized then banner 9 will be held in the position as shown, that is, in the non-visible position, which corresponds with the absence of a train from the section composed of rails 1 and 2 and the energized condition of relay 4, so that one approaching 45 the signal would receive no warning, furthermore, under such conditions no warning is needed. It being understood that the section composed of track rails 1 and 2 would 50 be so located, as is well understood by those skilled in the art to which this invention relates, that a train approaching the crossing would enter the section before arriving at the crossing.

55 If, while all parts were in the positions and condition as illustrated by Fig. 1, a train or car should enter upon track rails 1 and 2, then as is well understood, the relay 4 would be deenergized and its armature 7 would fall so as to break contact with wire 33 and make contact with wire 8. This movement of armature 7 would result in deenergizing magnet 25, because the circuit including magnet 25 and battery 34 would be broken. 60 65 The circuit which is called the retaining

circuit when closed is as follows—positive terminal of battery 34, wire 35, armature 7, wires 33 and 36, magnet 25, and wires 37, 38 and 39 to the negative terminal of battery 34.

70 The breaking of the retaining circuit and consequent deenergization of magnet 25 causes the attractive force exerted on armature 26 to cease, whereupon weight 28 causes clutch arm 27 to oscillate about shaft 24 as a pivot until crank arm 32 comes in contact with stop pin 40, at which time banner 9 is in the visible or caution position thus indicating to one approaching the crossing that a train or car may also be approaching the 80 crossing so giving the warning so desirable and in fact absolutely necessary in such a case.

85 When clutch arm 27 is allowed to oscillate as hereinbefore described, the insulating projection 29 is so moved that conductive contact finger 30 is allowed to fall in contact with wire 41.

90 If the train which caused banner 9 to move to the visible position passes off from the rails 1 and 2 then relay 4 will again be energized, as is well understood, and armature 7 will be raised to contact with wire 33. Immediately this occurs an operating 95 circuit will be formed as follows—positive terminal of battery 34, wire 35, armature 7, wires 33 and 42, motor 12, wire 43, brake magnet 44, wire 41, conductive contact finger 30 and wires 45 and 39 to the negative terminal of the battery 34.

100 It will be noted that the operating circuit includes brake magnet 44. This brake magnet has, in proximity to the upper end of its core 46, an armature 47 which is suspended from a brake lever 48, pivoted at 49 and spring pressed upwardly by the expansion spring 50 the lower end of which bears against a fixed point. The brake lever 48 on the right of its pivot has attached thereto a brake block 51, which bears against the periphery of a disk-like part forming a brake-drum forming part of the armature 52 of the motor 12 when the brake lever is pressed upwardly by the spring 50 so as to prevent rotation of the armature. When the 110 operating circuit above traced is formed however, the armature 47 is moved downwardly and the brake block 51 upwardly so that the armature and shaft of the motor are free to rotate.

115 The operating circuit above traced, when the brake block 51 is moved out of contact with the armature causes the armature and shaft of the motor to rotate and through the train of gears 14, 15, 17 and 18 causes 125 link 21 to pull the lower end of operating arm 23 downwardly and the upper end upwardly so that the magnet 25 thereon comes in contact with armature 26 which had previously been separated therefrom by the 130

passage of a train onto rails 1 and 2. Under the conditions assumed, that is with relay 4 energized, the magnet 25 will be energized by the retaining circuit herein before described, consequently, when arm 23 begins to descend due to the passage of crank pin 20 through more than one hundred eighty degrees of arc, it will drag armature 26 and clutch arm 27 with it so that banner 9 through crank 32 and link 31 will be moved toward the position shown in Fig. 1. During the movement, insulated projection 29 will contact with conductive contact finger 30 and by properly positioning insulated projection 29 the conductive finger 30 can be made to break contact with wire 29 and so break the operating circuit at just the right moment so that the breaking of the operating circuit will deenergize brake magnet 44 at just the right time to cause brake block 51 to be applied to the armature of the motor 12 so that all parts will come to rest in the position shown in Fig. 1.

In order to illuminate the signal banner, especially at night, applicant has provided an electric lamp. When the relay 4 is deenergized the armature 7 falls and makes contact with wire 8 so that a circuit for illuminating the lamp is formed as follows: positive terminal of battery 34, wire 35, armature 7, wire 8, lamp 53 and wires 54, 38 and 39 to the negative terminal of the battery 34.

It should be noted that a failure of either the track battery 3 or operating battery 34 or any of their connections will result in displaying the visible position of the banner 9 because either of these occurrences results in deenergizing magnet 25. In fact the bias of the banner by reason of weight 28 is to the visible position so that all failures are on the safe side that is to tend to cause the banner to be rotated to visible position. It being well understood by those skilled in the art to which the invention relates that upon a failure in this class of apparatus the exhibition of a caution signal is the best practice.

Although I have particularly described the construction of one physical embodiment of my invention, and explained the operation and principle thereof, nevertheless, I desire to have it understood that the form selected is merely illustrative, but does not exhaust the possible physical embodiments of the idea of means underlying my invention.

What I claim as new and desire to secure by Letters Patent of the United States, is—

1. In a railway highway crossing signal, in combination: a banner formed with a face of distinctive and arrestive appearance and extent and practically an edge of non-

distinctive and non-arrestive appearance and of comparatively slight extent; an oscillatable clutch arm having a normal bias; means connecting the clutch arm and the banner whereby when the clutch arm assumes its biased position it will cause the banner to exhibit the face; an oscillatable operating arm; means for clamping together the operating arm and the clutch arm whereby the clutch arm cannot move in response to its bias except by a corresponding movement of the operating arm and means for preventing movement of the operating arm whereby the edge of the banner is exhibited.

2. In a railway highway crossing signal, in combination; a banner formed with a face of distinctive and arrestive appearance and extent and practically an edge of non-distinctive and non-arrestive appearance and of comparatively slight extent; an oscillatable clutch arm having a normal bias; means connecting the clutch arm and the banner whereby when the clutch arm assumes its biased position it will cause the banner to exhibit the face; an oscillatable operating arm: means for oscillating said operating arm to contact with said clutch arm when said clutch arm is in biased position; means for clamping together the clutch arm and operating arm when they contact whereby further movement of the operating arm moves the clutch arm correspondingly, the said second mentioned means oscillating the operating arm to such an extent that the said banner exhibits the edge.

3. In a railway highway crossing signal, in combination; a banner formed with a face of distinctive and arrestive appearance and extent and practically an edge of non-distinctive and non-arrestive appearance and of comparatively slight extent; an oscillatable clutch arm having a normal bias; means connecting the clutch arm and the banner whereby when the clutch arm assumes its biased position it will cause the banner to exhibit the face; an oscillatable operating arm; means for oscillating said operating arm to contact with said clutch arm when said clutch arm is in biased position; a magnet attached to the operating arm; an armature attached to the clutch arm; means for energizing the magnet whereby when the said operating arm and clutch contact they will be clamped together magnetically whereby further movement of the operating arm moves the clutch arm correspondingly, the said second mentioned means oscillating the operating arm to such an extent that the said banner exhibits the edge.

4. In a railway highway crossing signal, in combination; a banner formed with a face of distinctive and arrestive appearance and extent and practically an edge of non-

and extent and practically an edge of non-distinctive and non-arrestive appearance and of comparatively slight extent; an oscillatable clutch arm having a normal bias; 5 means connecting the clutch arm and the banner whereby when the clutch arm assumes its biased position it will cause the banner to exhibit the face; an oscillatable operating arm; means for oscillating said 10 operating arm to contact with said clutch arm when said clutch arm is in biased position; a magnet attached to the operating arm; an armature attached to the clutch arm; means for energizing the magnet 15 whereby when the said operating arm and clutch contact they will be clamped together magnetically whereby further movement of the operating arm moves the clutch arm correspondingly, and means controlled by the 20 clutch arm whereby further oscillation of the operating arm ceases when the clutch arm reaches a position in which the said banner exhibits the said edge.

5. In a railway highway crossing signal, 25 in combination: a banner formed with a face of distinctive and arrestive appearance and extent and practically an edge of non-distinctive and non-arrestive appearance and of comparatively slight extent; an oscillatable clutch arm having a normal bias; 30 means connecting the clutch arm and the banner whereby when the clutch arm assumes its biased position it will cause the banner to exhibit the said face; an oscil-

latable operating arm; an electric motor for 35 oscillating said operating arm so that it will contact with the clutch arm when the clutch arm is in biased position; a circuit for said motor; a source of current included in said circuit; a circuit controller in said circuit 40 which when closed closes the circuit for said motor; a brake magnet in said circuit; a brake block controlled by said brake magnet and preventing operation of said motor when said circuit is open but allowing operation of said motor when said circuit is closed; means connecting the operating arm and the motor whereby an operation of the motor causes an oscillation of the operating arm when the brake block does not prevent movement of the motor; a magnet attached to the operating arm; a circuit including 45 said magnet and a source of energy; an armature attached to the clutch arm whereby when the operating arm and the clutch arm contact they will be held together magnetically whereby further movement of the operating arm will move the clutch arm correspondingly; means controlled by the clutch arm for opening the circuit including the 50 motor and the brake magnet whereby further oscillation of the operating arm ceases when the clutch arm reaches a position in which the said banner exhibits the said edge and means for controlling the circuit for 55 energizing the magnet and the circuit including the motor.

STANLEY CHARLES BRYANT.
